SHOE DISPLAY EASEL

Morris D. Pollinger, Stamford, Conn.

Application November 24, 1936, Serial No. 112,477

5 Claims. (Cl. 211—37)

This invention relates to display devices and refers more particularly to an improved display easel for shoes by virtue of which the same may be supported at an angle coinciding approximately with the angle at which a shoe is viewed by the wearer when being worn.

The invention broadly aims to provide a display easel by means of which a shoe is supported at an angle to a horizontal bearing surface with the upper part of the shoe displayed and the heel portion downwardly corresponding to the angle from which the wearer visualizes the shoe as worn by him, the easel being so constructed and arranged as to afford a stable support while substantially concealed from view.

More particularly the invention comprehends a display easel for shoes which is readily collapsible from a set up condition to a compact folded arrangement for storage and shipment.

As a further feature the invention resides in an improved easel for the purpose specified which is constructed from a minimum of simple parts whereby the same may be economically produced and assembled and which is highly efficient for its intended purpose.

With the above enumerated and other objects in view, reference is now made to the following specification and accompanying drawing in which there is disclosed by way of example, a preferred embodiment of the invention, while the appended claims cover variations and modifications thereof which fall within the scope of the invention.

In the drawing:

Fig. 1 is a perspective view of an easel constructed in accordance with the invention, illustrating a shoe supported thereby for display.

Fig. 2 is a similar view thereof on a larger scale with the shoe removed.

Fig. 3 is a rear face view of the easel illustrating the parts in folded or collapsed condition.

Fig. 4 is a side edge view thereof.

Fig. 5 is a fragmentary sectional view taken approximately on the line 5—5 of Fig. 2.

Referring to the drawing by characters of reference, the easel includes a body member designated generally by the reference character A and a prop member designated generally by the reference character B, each of which members is preferably fashioned from sheet metal or any other equivalent material adapted for the intended purpose.

The body member A has a straight lower marginal edge 10 adapted to engage with the easel supporting surface and has curved opposite side edges 11 which merge into upwardly converging

side edges 12 terminating in a rounded upper edge 13 to provide an elongated structure in which the lower portion thereof conforms generally to the shape of the shoe heel. This lower portion is provided with oppositely disposed upstanding marginal lugs 14 which are preferably formed integral with the body member and which are provided with roughened or serrated inner surfaces 15, which surfaces diverge toward the upper end of the body member so as to engage 10 with the opposite sides of the arcuate rear portion of the shoe heel and thereby support the shoe so that the heel is slightly elevated above the supporting surface.

The tread portion of the heel and ball of the 15 shoe is designed to rest upon the upper surface of the body member A which is also roughened or serrated as at 16 adjacent its upper end. Preferably, the body A is provided with upper and lower cut-out portions 17 and 18 in order to lighten 20 the weight of the same, thereby leaving between the two cut-out portions a transverse cross piece 19 which in addition to strengthening the structure, serves as a mounting for the prop member B.

In order to strengthen the body member longitudinally, rearwardly depressed linear beads 20 are formed in the body parallel to the upwardly converging marginal edges 12. The prop member B is of substantially rectangular configuration and is formed with a substantially V-shaped notch 21 opening through the upper end thereof and defining a pair of furcations 22 having angularly disposed hooked terminals 23 which, by flexing of the furcations towards each other, are 35 engaged in slots 24 in the cross piece 19. This swingably attaches the prop member B to the body member A whereby the same may be swung from the active supporting position shown in Figs. 1, 2 and 5, to the inactive folded positions 20 shown in Figs. 3 and 4 where the prop lies parallel to the body in order to occupy a minimum amount of space for storage and shipment.

The outer sides of the furcations 22 are rabbed at 25 and the rabbeted portions are 45 formed with upturned stop ears 26 which are designed to engage with the rear or undersurface of the body member A to limit the opening movement of the prop member and sustain the body member at a predetermined angle which corresponds approximately to the angle at which a shoe is directly viewed when on the foot of the wearer. This angularity may be slightly varied, if desired, by bending the stop ears 26 forwardly 50

or rearwardly of the length of the prop member.

What is claimed is:

1. A shoe display easel including an elongated body of sheet material upon one surface of which the tread portions of the shoe are adapted to

5 rest, rearwardly directed prop means for supporting the same at an angle to a supporting surface, and oppositely disposed upstanding lugs on opposite side edges of said body, spaced 10 above the lower supporting edge thereof and having their inner surfaces diverging towards the upper end of the body for engagement with the opposite sides of the arcuate rear portion of the shoe heel.

15 2. A shoe display easel including an elongated body of sheet material of gradually decreasing width from the lower portion thereof to the upper end and upon one surface of which the tread portions of the shoe are adapted to rest, a rear-

wardly directed prop means for supporting the same at an angle to a supporting surface, and oppositely disposed upstanding marginal lugs at 20 the lower portion of the said body having roughened inner surfaces diverging towards the upper

25 end of the body for engagement with the opposite sides of the arcuate rear portion of the shoe heel.

3. A shoe display easel including an elongated body having a straight lower edge adapted to en-

30 gage with a supporting surface, the lower portion of said body conforming generally to the shape of the shoe heel and having oppositely disposed upstanding marginal lugs, the inner surfaces of which diverge upwardly and are

35 adapted to engage with opposite sides of the

arcuate rear portion of the shoe heel, the upper portion of said body underlying the ball of the shoe, and a rearwardly directed prop for supporting the body at an angle to said supporting surface.

4. In a shoe display easel, an elongated body member upon which the shoe is adapted to rest, and a prop member having bifurcated upper ends formed with hooked terminals, slotted portions 10 of the body member with which the hooked terminals are engaged to connect the body and prop for relative swinging movement from an active rearwardly directed angular position to an inactive folded position, and upstanding stop means on said member for limiting the opening 15 movement thereof.

5. A shoe display easel fashioned from sheet material and including an elongated body member upon which the tread areas of the heel and ball portions of the shoe are adapted to rest, 20 oppositely disposed upstanding marginal lugs adjacent the lower portion of the body member having inner surfaces diverging towards the fore-part of the body for engagement with opposite sides of the arcuate rear portion of the heel, and 25 a prop member having a bifurcated forward end and angularly disposed hooked terminals at the extremity of each furcation, slotted portions of the body member into which said terminals are sprung to swingably connect the prop therewith, 30 and an upstanding stop ear on each furcation adapted to engage with the body member for limiting the angular disposition of the prop with reference thereto.
